UNITED STATES PATENT OFFICE

90,476

DESIGN FOR A WATERPROOF CIGARETTE CASE

Gennaro Castellano and Otto Esposito,
New York, N. Y.

Application April 27, 1932. Serial No. 43,638

Term of patent 7 years

To all whom it may concern:

Be it known that we, GENNARO CASTELLANO and OTTO ESPOSITO, both citizens of the United States, and residents of New York, in the county of New York and State of New York, have invented a new, original, and ornamental Design for a Waterproof Cigarette Case, of which the following is a specification, reference being had to the accompanying drawing, forming part thereof.

Figure 1 is a side elevation of a waterproof cigarette case, showing my new design,

Figure 2 is an edge elevation thereof, and

Figure 3 is a top plan view thereof.

We claim:

The ornamental design for a waterproof cigarette case, as shown.

GENNARO CASTELLANO.
OTTO ESPOSITO.
